UNITED STATES PATENT OFFICE.

LEROY S. MUNGER, OF HUMBOLDT, KANSAS.

ADDING-MACHINE.

No. 857,889.

Specification of Letters Patent.

Patented June 25, 1907.

Application filed May 21, 1906. Serial No. 317,951.

To all whom it may concern.

Be it known that I, LEROY S. MUNGER, a citizen of the United States, residing at Humboldt, in the county of Allen and State of Kansas, have invented certain new and useful Improvements in Adding-Machines, of which the following is a specification.

My invention relates to that class of adding-machines adapted to be used in connection with any standard typewriting machine now on the market, but if desired may be supplied with key-levers and used independently of said typewriting machine.

The invention embodies a series of adding-wheels and a master-wheel, which latter is adapted to successively engage and operate said adding-wheels so that the amounts of the items written upon the typewriter are simultaneously added, the depression of a numeral key effecting both the writing of the number and its registration. The registering mechanism, moreover, can be moved into or out of operative position at the will of the operator, so that the typewriter can be used to record dates or totals without disturbing the adding mechanism.

To this end the invention comprises the actuating mechanism by which the depression of a key-lever sets in motion instrumentalities which register and add its number; the motor, and winding mechanism by which power is stored therein by the return movement of the carriage; and the registering mechanism connected with the above and consisting of a master wheel, the adding-wheels with their lock and its trip, the resetting mechanism, and the carrying mechanism. These parts will be described below in the order given.

The invention further consists in the novel construction, combination, and arrangement of parts hereinafter described, claimed, and illustrated in the accompanying drawings; and in order that it may be readily understood reference will now be made to said drawings, in which:

Figure 1 represents a broken front elevation of a typewriter with my adding-machine connected thereto. Fig. 2 is an irregular vertical transverse section of the adding-machine taken on line II—II of Fig. 3. Fig. 3 is a plan view of same with the case in section, said section being taken on line III—III of Fig. 2. Fig. 4 is an enlarged broken longitudinal section on line IV—IV of Fig. 3,

showing the mechanism for restoring the adding-wheels to normal. Fig. 5 is a vertical transverse section on line V—V of Fig. 4. Fig. 6 is a broken plan view of that portion of the adding-machine underlying the typewriter. Fig. 7 is a broken transverse section on line VII—VII of Fig. 6, showing means for limiting the rotary movement of a master-wheel employed in operating the adding-wheels. Fig. 8 is a cross-section on line VIII—VIII of Fig. 6, showing part of a train of gear-wheels for operating the master-wheel. Fig. 9 is a detail plan view of a portion of the carrying-mechanism employed in carrying out the invention. Fig. 10 is a section on line X—X of Fig. 3, showing a spring-motor and a cog-wheel forming part of a train of gear-wheels for driving the master-wheel. Figs. 11 and 12 are enlarged transverse sections on lines XI—XI and XII—XII, respectively, of Fig. 6, showing a slotted-roller for limiting the movement of the spring-motor and said train. Fig. 13 is a detail front elevation of the master-wheel and a yoke for shifting said gear to and fro upon its shaft. Fig. 14 is a section on line XIV—XIV of Fig. 1, showing a portion of the gearing for shifting said yoke and winding the spring-motor. Fig. 15 is a detail of one of the locking devices for holding the adding-wheels from accidental movement.

A designates the frame of a typewriting machine, of any standard make, provided with a carriage-scale B and numeral key-levers 1 2 3 4 5 6 7 8 and 9 for printing corresponding numbers. In the application of my invention thereto, said key-levers have depending stems 10 provided with inverted heads 11 rigid with their lower terminals and arranged in a row as shown in Fig. 6.

Actuating mechanism.—12 designates a slotted-roller underlying the key-stems and provided with peripheral slots 13 14 15 16 17 18 19 20 and 21 which vary in length from one to nine-tenths of the periphery in the order above enumerated. Said slots terminate in rectangular openings 22 23 which latter communicate with the forward terminals of said slots and are arranged in a row beneath heads 11 to receive the same one at a time, when the key-levers are depressed. By providing the keys with headed stems none of the latter can become disengaged from their respective slots until the roller has turned the length of the engaged slot, it also

insures the proper operation of the adding-machine as one lever cannot be depressed while another has its stem in engagement with its respective slot. As shown in Fig. 6 5 the slots are arranged according to their length in proper relation to the key-levers, for instance, slot 13 which extends around but one-tenth of the periphery of roller 12 is arranged beneath lever 1, while slot 21 10 which extends around nine-tenths is placed beneath key 9.

Roller 12 is mounted upon a shaft 24 and restored to normal by a spring 25, after being turned forwardly as hereinafter described. Said spring is secured at its ends to shaft 24 and the adjacent side of a vibratory frame 26. Backward movement of the roller is limited by a radial pin 27, projecting therefrom, and a stop 28, the former impacting against the latter after openings 23 20 have been returned in coincidence with heads 11 as shown in Fig. 6.

Frame 26 comprises a pair of bearings 29 in which shaft 24 is journaled, a longitudinal bar 30 carrying bearings 29 and stop 28, a 25 pair of arms 31 extending rearwardly from said bar, and a longitudinal bar 32 carried by the rear ends of arms 31. Bearings 29 have trunnions 33 mounted in a supporting-frame 34, and bar 32 is provided with a series 30 of upwardly-extending seats 35 in which key-levers 1 to 9, inclusive, rest, thus when any one of said levers is depressed frame 26 will be rocked upon its trunnions and move 35 roller 12 upwardly to meet the descending key-stem so that the latter may engage its respective slot. When the key-lever is released and returns to its normal position the entire rear portion of frame 26 will be over- 40 balanced by its heavier forward portion and said rear portion will move upwardly with said key-lever until the latter comes to rest. Seats 35 are provided with flanges 36 loosely 45 embracing the sides of the key-levers to prevent lateral movement of the latter upon said seats. Frame 34 is provided with sockets 37 to receive the feet of the typewriting machine so that the latter cannot shift upon said frame.

50 38 designates an arm (Fig. 12) fixed at its rear end to the right-hand trunnion 33, and having its forward end curved upwardly and terminating near the lower end of an adjustable screw 39 extending through a detent 40 having its rear end normally held in engagement with an escape-wheel 41 by means of a retractile-spring 42.

One end of shaft 24 extends through arm 38 and is provided with a fixed pinion 24^a 55 which is raised upwardly into mesh with a cog-wheel 43 when the rear end of frame 26 is depressed by a key-lever. Screw 39 is so adjusted that when one of the key-levers say, for instance, lever 6 is depressed arm 38 60 will engage and move said screw 39 upwardly

to disengage detent 40 from escape-wheel 41 just after pinion 24^a intermeshes with cog-wheel 43. When the latter operation occurs the cog-wheel 43 will rotate the pinion and the slotted roller until the movement of said 70 roller is arrested by the end of slot 18 contacting with the engaging key-stem. Key-lever 6 will then be free to move upwardly out of engagement with said slot and permit the forward end of frame 26 to swing downwardly and carry pinion 24^a out of engagement with wheel 43, and arm 38 out of engagement with screw 39 so that spring 42 75 may throw the detent upwardly into engagement with the escape-wheel and thus prevent further rotation of the latter. Screw 39 is so adjusted that the detent will engage the escape wheel before pinion 24^a has fully disengaged wheel 43. From the above it will be understood that the rotary movement of the slotted-roller is limited by the 80 length of the slots therein and their respective key-stems.

Motor.—Escape-wheel 41 and cog-wheel 43 (Fig. 3) are fixed upon one end of a counter-shaft 44, provided at its opposite end with a fixed pinion 45 driven by a cog-wheel 46 loosely mounted upon a main shaft 47, intermittently driven by a spring-motor 48, one 90 end of which is secured to said shaft while its opposite end is fixed to the base 49 of a case 50 inclosing the adding mechanism. (See Fig. 10.) Spring 48 is normally held from unwinding by escape-wheel 41 and the intervening train of cog-wheels, the diameters of which are such that when roller 12 rotates nine-tenths of a revolution cog-wheel 46 will rotate but a small fraction of this distance.

Winding mechanism.—Spring-motor 48 is 105 wound when the typewriter-carriage is moved to the right, through the instrumentality of a train of gearing comprising a rack-bar 51, a pinion 52 meshing therewith and fixed upon one end of a shaft 53, (Figs. 1 and 4) a cog-wheel 54 also fixed upon said shaft, a rack-bar 55 having two rows of teeth 56 57 the latter of which meshes with cog-wheel 54, while the former meshes with a cog-wheel 58 fixed upon one end of a shaft 59, a bevel-gear 60 fixed upon the opposite end of shaft 59 and intermeshing with a similar bevel-gear 61 fixed upon the upper terminal of a shaft 62, a bevel-gear 63 (Fig. 3) fixed upon the lower end of shaft 62 and intermeshing 110 with a bevel-gear 64 loosely mounted upon shaft 47, a ratchet-wheel 64^a fixed to said shaft, and a pawl 64^b carried by cog-wheel 46. Pinion 52 is elongated as shown in Fig. 14, so that when the carriage is shifted backwardly from the lower to the upper case of letters rack-bar 51 will not pass backwardly 115 far enough to disengage said pinion.

The left end of rack-bar 51 loosely embraces scale B to which it is adjustably se- 120

cured by a set-screw 65, so that when it is desired to arrange the carriage for printing columns of figures either at the left or right side of the paper said carriage may be shifted by 5 loosening screw 65, without disturbing the proper relation of the rack-bar with pinion 52.

After the carriage has been properly adjusted screw 65 is again tightened so that the 10 rack-bar will be shifted to the right or left with the carriage when printing the numerals from 1 to 9, inclusive, without disengaging said rack from its pinion. The toothed end of rack-bar 51 is supported by a pin 66 projecting from scale B through a longitudinal slot 67 arranged in the rack-bar to permit the adjustment of the latter upon the scale. Rack-bar 51 is held downwardly in mesh with pinion 52 by an overlapping clip 68 secured to the upper portion of a bracket 69 fixed to the upper portion of the typewriter. Bracket 69 is provided with a guide 70 which embraces rack-bar 55 and holds it in mesh with wheel 54. Bevel-gear 64 is provided 15 with a stud 71 adapted to engage a pin 72 projecting radially from shaft 47, and thus rotates the latter to wind the spring-motor when said bevel-gear turns in the direction indicated by the dotted arrow, Fig. 3.

20 The above described mechanism allows spring 48 to be wound without disturbing cog-wheel 46, roller 12, or the intervening train of gearing, as pawl 64^b permits the ratchet-wheel 64^a to turn and wind the spring-motor without affecting cog-wheel 46. 25 Ratchet-wheel 64^a, pawl 64^b, cog-wheel 46, and the train of gear-wheels between said cog-wheel and escape-wheel 41 prevent the spring-motor from unwinding until 30 detent 40 is tripped out of engagement with the escape-wheel.

35 *Masterwheel.*—75 designates a pinion intermeshing with and driven by cog-wheel 43. Said pinion is the same diameter as pinion 24^a so that it will turn the master-gear-wheel 45 78 an equal distance with roller 12, and is fixed upon one end of a shaft 76 extending through case 50 and journaled in the sides thereof, said shaft being rectangular in cross-section throughout its length except at its 50 journaled ends so that the master-wheel may slide thereon and turn therewith.

55 77 designates a yoke (Fig. 13) embracing the sides of master gear-wheel 78 for the purpose of shifting the latter upon shaft 76. Yoke 77 is held in an upright position by two 60 guide-bars 79 (Fig. 3) upon which it slides, it being moved to and fro upon said guide-bars by an arm 80 normally secured to rack-bar 65 55 by a set-screw 81—Fig. 1. Yoke 77 is provided at its front side with a stud 82 and at its rear side with a rearwardly projecting arm 83 and a lug 84 which latter has a bevel surface 85.

65 *Adding wheels.*—86 87 88 89 designate add-

ing-wheels representing tenths, units, tens and hundreds, respectively, and consisting of disks 90, each of which bear numerals "0" to "9", and cog-wheels 91, which latter are arranged to be engaged and turned, one at a time, by master-wheel 78 during an adding operation. Said adding-wheels are journaled upon a shaft 92 which extends loosely through a frame 93 and one side of case 50, its outer end having a knob 94 and a pin 95 which latter normally engages a slot 96 in a socket 97 to prevent the shaft from turning with the adding-wheels.

70 *Lock.*—When master-wheel 78 is at the end of its movement to the left, the teeth of cog-wheels 91 are held in alinement by a plurality of detents 105 so that said master-wheel may successively mesh with the cog-wheels as it moves to the right. Detents 105 are fixed upon pintles 106 journaled in the front side of 75 casing 50 and in a bar 107 in which said pintles fit friction-tight so they will not accidentally turn in their bearings. Bar 107 is secured to the rear side of frame 93.

80 *Lock Trip.*—The detents are thrown in and out of engagement with the cog-wheels through the instrumentality of the stud 82 on yoke 77 and a plurality of bell-crank levers, which latter are fixed upon the pintles and comprise arms 108 109—Fig. 15. 85 When the master-wheel moves to the right and successively engages the cog-wheels arms 108 stand upwardly in the path of stud 82, thus as the master-wheel engages each cog-wheel said stud will release the same so 90 that it may rotate with the master-wheel.

95 *Resetting mechanism.*—After completing the addition of a column of items it may be desirable to restore the adding-wheels to normal preparatory to adding another column, 100 so I provide shaft 92 with a series of radially-extending pins 98 which are drawn into contact with the adjacent sides of the disks when the shaft is pulled outwardly to withdraw pin 95 from slot 96 as shown by dotted lines 105 Fig. 4. This also brings them in the path of lugs 99 on the disks, so that by turning the shaft in the direction indicated by the arrow, Fig. 5, said pins 98 will contact with the lugs 110 and turn the adding-wheels until the lugs 115 contact with a like number of stops 100 which prevent further rotation of the adding-wheels and cause them to stop with their ciphers in coincidence with a sight-slot 101 in case 50. This also brings pin 95 in coincidence with 120 slot 96 so that when the knob is released an expansion spring 102 may force the shaft inwardly until pin 95 engages the inner end of its slot. The inward movement of the shaft will carry pins 98 and stops 100 into 125 recesses 98^a and 100^a, respectively, in frame 93, so that they will be out of the paths of lugs 99. Stops 100 depend from a bar 103 130 slideably arranged in frame 93 and provided with a downwardly-extending arm 104, the

lower end of which loosely engages the shaft but is caused to move in and out therewith by collars 104^a.

108 109 designate arms comprising bell-crank levers fixed to the pintles 106 for the purpose of throwing the detents 105 in and out of engagement with cog-wheels 91. When the master-wheel is at the left the bell-crank levers arms 108 are uppermost so that when 10 said master-wheel is shifted to the right to add an item, stud 82, which is in advance of the master-wheel, will successively depress said arms and cause them to throw detents 105 out of engagement with cog-wheels 91 15 so that the latter may be rotated by the master-wheel. The depression of arms 108 brings arms 109 uppermost, as shown in Fig. 4, so that when the master-wheel is shifted to the left stud 82 will successively 20 depress said arms 109 and cause them to throw the detents into engagement with cog-wheels 91 as the master-wheel passes out of engagement with each of the latter. Arms 109 are thinner than arms 108 so they may 25 swing up or down without contacting with studs 110 projecting rearwardly from bar 103 for the purpose of unlocking the adding-wheels preparatory to restoring the latter to normal and for locking the same after being 30 restored. As the restoration of the adding-wheels to normal is accomplished when the master-wheel is at the left end of its movement, it follows that arms 108 are uppermost and in the path of studs 110, hence 35 when bar 103 is drawn outwardly said studs will depress arms 108 and thus unlock the adding-wheels. After the latter have been restored to normal they are locked on the inward movement of bar 103, which, carrying 40 the studs 110 to the left, cause them to engage shoulders 109^a integral with arms 109 and thus depress the latter. As bar 103 moves a short distance to the left after arms 109 have been lowered to a horizontal position, 45 studs 110 will be carried far enough to the left of shoulders 109^a to permit the latter to swing upwardly without contacting with said studs when arms 108 are depressed by stud 82.

50 *Carrying mechanism.*—The disks of adding-wheels 86 87 and 88 are provided with peripheral studs 111 which are brought into engagement with the upper surface of the rear terminals of a like number of trip-levers 112 when the adding-wheels are restored to normal. Said trip-levers are pivoted at their forward ends upon a rod 113 secured in a pair of standards 114. The trip-levers are provided with lugs 115 extending to the left 55 and engaging shoulders 116 on the forward ends of pull-bars 117 underlying adding-wheels 87 88 89 and extending through slots 118 119 in the front side of frame 93 and a guide-bar 120, respectively. Pull-bars 117 65 are provided with slots 121 in which are piv-

otally secured rack-bars 122 which engage the cog-wheels of adding-wheels 87 88 89 after the detents 105 have been thrown out of engagement with the same, and thus alternate with said detents in holding the teeth 70 of the cog-wheels in alinement so that the master-wheel may successively mesh therewith. Said rack-bars also cause the adding-wheels to carry-over as will hereinafter appear. 75

The teeth of the adding-wheel 86 are held in alinement with those of the other cog-wheels by a rack-bar 122^a pivotally mounted in a slot 121^a in a stationary bar 117^a—Fig. 3. All of the rack-bars are raised into engagement with the adding-wheels by means of crank-arms 123 (Fig. 2) pivotally mounted upon a rod 124 and provided with shoulders 125 126 which limit their upward and downward movements. The crank-arms are raised 85 and lowered by connecting-bars 127 pivotally secured at their opposite ends to said crank-arms and arms 128, which latter are fixed upon upright pintles 129 mounted in bearings 130. When the connecting-bars are 90 pushed forwardly they raise the crank-arms until shoulders 125 contact with said connecting-bars, and when the latter are drawn backwardly they lower the crank-arms until shoulders 126 engage the forwardly projecting 95 ends of said connecting-bars. When the crank-arms are lowered the rack-bars drop out of engagement with the cog-wheels and rest upon pins 133 extending across slots 121 100 121^a.

The pintles 129 are alternately turned to the right and left by bell-crank levers fixed to their upper portions and in order to prevent said levers from contacting with each other I arrange them in different planes as 105 shown in Fig. 2. Said levers comprise arms 131 132 which latter project into the path of the lower end of arm 83 on yoke 77 when it is at the left of said levers. When the master wheel, in moving to the right, passes out of mesh with a cog-wheel 91 the latter will be immediately locked by its respective rack-bar which is raised into mesh therewith by arm 83 contacting with arm 132 and pushing the same rearwardly to the position shown in 115 Fig. 3. The rearward movement of arm 132 swings arm 131 into the path of arm 83, so that when the latter moves to the left with the master-wheel the cog-wheel 91 will be unlocked as the master-wheel moves into 120 mesh therewith. 110

When an adding-wheel, say for instance 87, completes a revolution its stud 111 will engage the underside of its respective trip-lever and raise the latter until its lug 115 125 disengages the pull-bar underlying adding-wheel 88. Thus released the pull-bar will be drawn forward by its spring 134, until its shoulders 135 contact with a plate 136 on the front side of frame 93. As the pull-bar 130

moves forwardly it will turn adding-wheel 88 one step through the instrumentality of the intervening rack-bar 122 and thus cause it to add one number. When the master-wheel is shifted to the left the bevel face 85 will contact with the roller 137 on the pull-bar and thus draw the latter backwardly until its shoulder 116 engages its respective lug 115. By employing this simple carrying mechanism the carrying-over may be effected almost synchronously throughout the series of adding-wheels. For instance, if they registered nine hundred and ninety nine and nine tenths, and one more was to be added the carrying-over would take place throughout the series in proper sequence.

Operation: In practice the master-wheel is shifted to the left by moving the carriage to the right preparatory to printing and adding a column of figures, this throws detents 105 into engagement with the adding-wheels and rack bars 122 out of engagement therewith. Assuming now that the item to be added is 125.6 the carriage is shifted until the master-wheel engages the first adding-wheel to the left, which represents the highest denomination. Key 1 is then depressed until its stem enters slot 13, and arm 38 releases detent 40 from the escape-wheel 41. Thus released the spring-motor 48 will rotate the master-wheel and the slotted-roller until the rear end of slot 13 contacts with the engaging key-stem, releases the latter and permits it to rise with its lever. As said lever moves up-

wardly the carriage through arm 80 automatically shifts the master-wheel into engagement with the next adding-wheel which is then turned two tenths of a revolution when key 2 is depressed. Thus by successively depressing levers 1, 2 5. the decimal key, and lever 6, the adding-wheels will accurately add the above-mentioned item to the one previously printed. When it is desired to print the total of a column of items without disturbing the adding-wheels the master-wheel is shifted either to the extreme left or right and either screw 65 or 81 is loosened so that said master-wheel will not shift with the carriage. As the adding-wheels are never operated through the action of the decimal key-lever a space is left between wheels 86 87 equal to the space between wheels 87 89, so that after numeral "five" of the above-mentioned item has been printed the master-wheel will be shifted, through the action of the carriage, midway between wheels 86 87, and after the decimal has been printed said master-wheel will be shifted into position to rotate wheel 86 and cause it to add the "six-tenths." By providing spring-motor 48 to actuate the adding mechanism the spacing mechanism of the typewriter will be relieved of all extra work except that of shifting the master-wheel, and consequently the speed of the typewriter will not be materially diminished. As the car-

riage is only shifted about one-tenth of an inch by the depression of a key-lever while the master-wheel must move about five-eighths of an inch in order to move from one adding-wheel to another, the length of the steps taken by the latter are compounded by properly proportioning pinion 52 and cog-wheel 54.

Having thus described my invention, what I claim and desire to secure by Letters-Patent, is:—

1. In an adding-machine, a series of toothed adding-wheels having a single set of teeth, locking mechanism for normally engaging said teeth to hold them in alinement, a master wheel adapted to successively engage the same set of teeth, means for rotating said master-wheel, a member for shifting the master-wheel, and means interposed between said member and the locking mechanism whereby the latter is operated by the former.

2. In an adding-machine, a series of toothed adding-wheels having a single set of teeth, detents for normally engaging said teeth to hold them in alinement, a master-wheel adapted to engage said teeth, means for rotating said master-wheel, a member embracing said master-wheel, means for shifting the yoke and master-wheel for throwing the latter successively into engagement with the teeth, and means interposed between said member and the detents whereby the latter is operated by the former.

3. In an adding-machine, a series of toothed adding-wheels, detents for normally holding the teeth of said adding-wheels in alinement, a master-wheel adapted to engage said teeth, means for rotating said master-wheel, a member for successively shifting the master-wheel into engagement with the teeth, and means interposed between said member and the detents whereby the latter are successively disengaged from the teeth as the master-wheel shifts in one direction, and are successively thrown into engagement with said teeth when the master-wheel shifts in the opposite direction.

4. In an adding-machine, a series of toothed adding-wheels, detents for normally holding the teeth of said adding-wheels in alinement, a master-wheel adapted to engage said teeth, means for rotating said master-wheel, a member for successively shifting the master-wheel into engagement with the teeth, bell-crank levers for operating the detents, and means interposed between the shiftable member and said bell-crank levers whereby the latter are actuated by the former.

5. In an adding-machine, a series of adding-wheels having a single set of teeth, locking mechanism for normally engaging said teeth to hold them in alinement, a master-wheel adapted to engage said teeth, and ro-

tate the adding-wheels, a yoke embracing said master-wheel, means for shifting the yoke and master-wheel for throwing the latter successively into engagement with the teeth of the adding-wheels, and means interposed between said yoke and the locking mechanism whereby the latter is actuated by the yoke.

6. In an adding machine, the combination with a series of adding wheels having teeth, carrying mechanism between them, a master wheel, and means for successively moving the latter into engagement with said adding wheels and rotating them; of detents adapted to engage said teeth, means connected with the master-wheel for tripping the detents, resetting mechanism, and means connected therewith for engaging all the detents with their adding wheels.

7. In an adding machine, the combination with a series of adding wheels having teeth, carrying mechanism between them, a master-wheel, and means for successively moving the latter into engagement with said adding-wheels and rotating them; of detents adapted to engage said teeth, and means connected with the master-wheel for tripping the detents as it moves in one direction and resetting them as it returns.

8. In an adding-machine, the combination with a typewriter and its carriage, of a series of adding-wheels, a master-wheel adapted to successively engage and rotate said adding-wheels, a motor for turning said master-wheel, a rack-bar carried by the typewriter carriage, gear-wheels driven thereby for winding the motor, and means interposed between said gear-wheels and the master-wheel whereby the latter is shifted by the former.

9. In an adding-machine, the combination with a typewriter and its carriage, of a series of adding-wheels, a master-wheel adapted to successively engage and rotate said adding-wheels, a motor for turning said master-wheel, a rack-bar adjustably connected with the typewriter carriage, gear-wheels driven thereby for winding the motor, and means interposed between said rack-bars and the master-wheel whereby the latter is shifted by the former.

10. In an adding-machine, the combination with a typewriter and its carriage, of a series of adding-wheels, a master-wheel adapted to successively engage and rotate said adding-wheels, a motor for turning said master-wheel, a rack-bar carried by the typewriter carriage, gear-wheels driven thereby, a second rack-bar shifted by said gear-wheels, and means actuated by said second rack-bar for shifting the master-wheel.

11. In an adding-machine, the combination with a typewriter and its carriage, of a series of adding-wheels, a master-wheel adapted to successively engage and rotate said adding-wheels, independent means for

turning said master-wheel, a rack-bar carried by the typewriter carriage, gear-wheels driven thereby, a second rack-bar shifted by said gear-wheels, an arm carried by the second rack-bar, and means actuated by said arm for shifting the master-wheel.

12. In an adding-machine, the combination with a typewriter and its carriage, of a series of adding-wheels, a master-wheel adapted to successively engage and rotate said adding-wheels, independent means for turning said master-wheel, a rack-bar adjustably carried by the typewriter carriage, gear-wheels driven thereby, a second rack-bar shifted at an increased speed by said gear-wheels, an arm detachably secured thereto, and a yoke carried by said arm and embracing the master-wheel.

13. In an adding-machine, the combination with a typewriter and its carriage and key-levers; of a series of adding-wheels, a master-wheel adapted to successively engage and rotate said adding-wheels, a spring-motor for rotating said master-wheel, a train of gearing actuated by the typewriter carriage for winding said spring-motor, an escapement connected with said train for normally locking said motor, and means controlled by the key-levers of the typewriter for releasing said escapement.

14. In an adding machine, a series of adding-wheels, a member adapted to successively rotate said adding-wheels, a motor for actuating said member, a roller controlling said motor and having a series of slots of different lengths with enlargements at their extremities, stems having heads adapted to said enlargements and limiting the rotation of said roller, key-levers carrying said stems, and means for restoring said roller to normal.

15. In an adding-machine, a series of adding-wheels, a member adapted to successively rotate said adding-wheels, a motor for actuating said member, a roller controlling said motor and having a series of slots of different lengths with enlargements at their extremities, stems having heads adapted to said enlargements and limiting the rotation of said rollers, a spring for restoring the roller to normal, and means for limiting the action of said spring.

16. In an adding-machine, the combination with a typewriter and its carriage, and key-levers; of a series of adding-wheels, a master-wheel adapted to successively engage and rotate said adding-wheels, a motor for rotating said master-wheel, means for winding the motor from the carriage, means for normally locking said motor, a vibratory member for releasing said means, a roller carried by said vibratory member, and connections between key-levers and roller.

17. In an adding-machine, the combination with a typewriter and its key-levers; of

- a series of adding-wheels, a master-wheel adapted to successively engage and rotate said adding-wheels, a motor for rotating said master-wheel, means for normally locking said motor, a vibratory frame and a slotted roller therein actuated by key-levers of the typewriter for releasing said means.
18. In an adding-machine, the combination with a typewriter and its key-levers; of a series of adding-wheels, a member adapted to successively rotate said adding-wheels, a motor for actuating said member, a spring-actuated roller for controlling the action of the motor by the degree of its rotation, and connections between certain key-levers and the roller for respectively limiting the rotation of the latter.
19. In an adding-machine, a series of adding-wheels, a member adapted to successively rotate said adding-wheels, a motor for actuating said member, a check for the motor, a roller also controlling said motor, and means for alternating the connection of the check and roller with the motor.
20. In an adding-machine, a series of adding-wheels, a member adapted to successively rotate said adding-wheels, a motor for actuating said member, a slotted roller controlling said motor, and a swinging frame supporting the roller normally out of engagement with said motor.
21. In an adding-machine, a series of adding-wheels, a member adapted to successively rotate said adding-wheels, a motor for actuating said member, a slotted roller controlling said motor, gears between them normally disengaged, a swinging frame supporting the roller and permitting said gears to engage, an escape wheel connected with the motor, a detent, and means for disengaging the detent from the escape wheel when said gears engage.
22. In an adding-machine, a series of adding-wheels, a member adapted to successively rotate said adding-wheels, a motor for actuating said member, a slotted roller controlling said motor, stems engaging the slots and limiting the rotation of said roller, and key-levers carrying said stems.
23. In an adding-machine, a series of adding-wheels, a member adapted to successively rotate said adding-wheels, a motor for actuating said member, a roller controlling said motor and having peripheral slots of different lengths, key-levers, stems carried thereby for engaging said slots, and means for preventing more than one slot being engaged at a time.
24. In an adding-machine, a series of adding-wheels, a member adapted to successively rotate said adding-wheels, a motor for actuating said member, a roller controlling said motor, and having slots with enlargements, stems having heads adapted to said enlargements and limiting the rotation of said roller, key-levers carrying said stems, and means for restoring said roller to normal.
25. In an adding-machine, a series of adding-wheels, a member adapted to successively rotate said adding-wheels, a motor for actuating said member, a roller controlling said motor, and having slots with enlargements, stems having heads adapted to said enlargements and limiting the rotation of said roller, a spring for restoring the roller to normal, and means for limiting the action of said spring.
26. In an adding-machine, a series of toothed adding-wheels, a master-wheel adapted to successively engage and rotate said adding-wheels, rack-bars adapted to engage and hold the teeth of the adding-wheels in alinement, and means for throwing the rack-bars into engagement with the teeth.
27. In an adding-machine, a series of toothed adding-wheels, a master-wheel adapted to successively engage and rotate said adding-wheels, rack-bars adapted to engage and hold the teeth of the adding-wheels in alinement, and means for successively throwing the rack-bars into engagement with the teeth.
28. In an adding-machine, a series of toothed adding-wheels, a master-wheel adapted to successively engage and rotate said adding-wheels, pivotally mounted rack-bars adapted to engage and hold the teeth of the adding-wheels in alinement, crank-arms for throwing the rack-bars into engagement with the adding-wheels, and means for operating said crank-arms.
29. In an adding-machine, a series of toothed adding-wheels, a master-wheel adapted to successively engage and rotate said adding-wheels, pivotally mounted rack-bars adapted to engage and hold the teeth of the adding-wheels in alinement, crank-arms for throwing the rack-bars into engagement with the adding-wheels, connecting-bars for operating said crank-arms, bell-crank levers for actuating said connecting-bars, and means for operating said bell-crank levers.
30. In an adding-machine, a series of toothed adding-wheels, a master-wheel adapted to successively engage and rotate said adding-wheels, rack-bars adapted to engage and hold the teeth of the adding-wheels in alinement, a member for shifting the master-wheel, and means interposed between said member and the rack-bars whereby the latter are thrown into engagement with the teeth.
31. In an adding-machine, a series of toothed adding-wheels, rack-bars engaging said adding-wheels, means for throwing said rack-bars into engagement with the adding-wheels, connecting bars for operating said

means, arms pivotally secured to the connecting-bars, bell-crank levers for operating said arms, a slideable master-wheel for successively engaging and rotating the adding-wheels, a member for sliding the master-wheel, and means carried by said member for actuating the bell-crank levers.

In testimony whereof I affix my signature, in the presence of two witnesses.

LERoy S. MUNGER.
